Brooklyn
Attorney

UNITED STATES PATENT OFFICE

HERBERT R. BRUNNER, OF NEW YORK, N. Y.

FUEL COMBUSTION

Application filed October 7, 1925. Serial No. 61,015.

My invention relates to fuel combustion; the object is to provide improved method and means for insuring a uniform and sufficient passage of air into the fuel bed to generate combustible gas out of the fuel bed, and also for carrying off the products of combustion from the combustion chamber without carrying off the unburnt gases, in such manner as to insure efficient burning within the combustion chamber, so as to utilize, to the fullest possible extent, the heat units resulting therefrom.

The invention is especially applicable for burning such fuels as buckwheat coal in domestic heating plants and comprises improved method and means for supplying air to the space beneath the fuel bed (the ash pit) of such ample volume and of such pressure only as to assure the even distribution and passage of the air into the fuel bed without appreciable assistance from the draft in the stack or chimney, and in so regulating the stack or chimney draft, and the supplemental air delivered to the combustion chamber, that all the gases delivered above the fuel bed, will be consumed in the combustion chamber and only the burnt products will be carried therefrom. In this manner the heat generated by the fuel combustion is utilized to the fullest possible extent.

The invention also comprises improvements in details of construction.

Referring to the drawings, which illustrate merely by way of example suitable means for effecting the invention:—

Fig. 1 is a part vertical section.

Fig. 1^a is a fragmentary view showing air inlet damper.

Fig. 2 is a top plan view.

Fig. 3 is a part plan view showing the ash door open.

Fig. 4 is a horizontal section of part of the device as shown in Figs. 1 and 2.

Similar numerals refer to similar parts throughout the several views.

In the arrangement shown in the drawings, the furnace 7 is of usual type having the door 8 opening to the ash pit 9. This door 8 is ordinarily provided with a draft opening 10, normally closed by a gravity actuated damper, the plane of the margins of the opening being inclined to the perpendicular. This damper being removed, an adapter 11 is secured to the door 8 and surrounds the margins of opening 10. The engaging margins of the adapter are, in the example, shown, in a corresponding inclined plane, while the main body of the adapter 11 has an approximately horizontal extension. To the opposite side of the adapter, from the side secured to the door 8, is secured the chambered body 12, which is shown substantially of rectangular formation. The front end of this body 12, is provided with the damper or door 13 and the adjusting arc and handle 14.

It will thus be seen that the adapter 11 and chambered body or box 12 form a self-containing unit secured to and entirely supported by the ash door of the furnace, and adapted to swing with the door when the same is opened and closed. The opening 10 is of ample dimensions, usually as large as the door 8 will conveniently permit. The throat of the adapter 11 is slightly larger than the opening 10. The throat or vertical cross-section of the chamber of body 12 is also slightly larger than opening 10. Within the chamber of body 12 is provided a ring or short cylinder 15, within which is suitably positioned a fan 16 supported and driven by the motor 17, secured and supported in any suitable way within the chamber of body 12, as by the spider 18. Between the chambered body 12 and the adapter 11 are provided the slidably shutters 19 for the adjustable control of communication between the ash pit 9 and the chamber of body 12. It will be noted that the adapter 11 and chambered body 12 are so proportioned and positioned as not to

interfere with ready access to the operating ends of the grates which are normally enclosed by a drop door as shown.

Above the fuel bed 20 is the combustion chamber 21 provided with the usual controlled air inlet 24, and the usual smoke pipe 22 connecting the combustion chamber to the stack or chimney flue, not shown. This smoke pipe is provided with a suitable 10 damper as at 23.

In operation, having a fuel bed of normal dimensions, composed of buckwheat coal or similar fuel, a volume and pressure of air is provided beneath the fuel bed to assure an 15 evenly distributed passage of the air into said fuel bed, and a delivery of gas therefrom into the combustion chamber above the fuel bed.

This volume and pressure is approximate- 20 ly adjusted, or relative to the mass and density of said fuel bed, in order that the proper amount of gas shall be generated from the fuel, for burning in the combustion chamber. This pressure depends very slightly, if 25 at all, upon the draft of the stack or chimney flue, since, in such case, the draft would tend to carry off from the combustion chamber a large amount of unburned gas, or products of combustion from which the heat units 30 had not been extracted, thus causing serious waste of heat units.

By creating a large volume of air, at a relatively low pressure, in the ash pit or space below the fuel bed, and utilizing a relatively 35 low pressure above the fuel bed, due to the stack flue, there is secured such a passage of air into the fuel bed as will result in a combustible gas delivered to the combustion chamber, above said fuel bed. This gas is 40 mixed with sufficient air, from the controlled inlet 13, or otherwise, for insuring combustion, so that the gases will be entirely burned within the chamber. The stack draft is so reduced that the products of combustion will 45 be retarded, or will idle through the heating spaces of the furnace and thus permit, to the fullest extent, heat transference from the products of combustion to the medium of heat circulation, such as air, water or steam, 50 as the case may be, and only the burnt products with most of the heat extracted therefrom, are carried away by the stack flue.

Merely by way of example, assume that 10/100 of an inch pressure were required to 55 cause the desired and evenly distributed passage of air to the coal bed, an ample volume of air is provided beneath the fuel bed, at a pressure of about 8/100 of an inch, permitting only about 2/100 of an inch pressure to 60 be created by the flue draft, in order to secure the conditions as above set forth. Whereas, if the entire pressure of 10/100 of an inch, necessary to cause the required flow of air through the fuel bed, were to be caused by 65 the flue draft, it will be seen that the suction

in the combustion chamber above the fuel bed, would result in carrying away the combustible gases, or even the burnt products so rapidly as to result in great heat losses, and this condition, in practically all domestic 70 heating plants burning such coal as buckwheat, has been found actually to exist.

My invention therefore consists essentially in providing a volume and creating a pressure of air beneath the fuel bed, the pressure 75 nearly or quite sufficient, never under any conditions excessive, to cause the evenly distributed passage of air into the fuel bed, and permitting the stack or chimney flue to exert a suction on the combustion chamber barely 80 sufficient to carry therefrom the products of combustion after having delivered to the circulating medium, the major portion of their heat units.

As a convenient means for carrying out 85 the invention, it should be noted that the pan is preferably designed, especially with respect to pitch or angle of blade, as to produce an approximately definite static pressure, under varying conditions, as for example, air spaces 90 of varying dimensions.

It will also be noted that the "booster unit" comprising the fan, its housing and associated elements, delivers to the regular and usual channel of the ash pit draft. It in no way 95 changes or alters this important function of draft, except to accelerate or boost the draft or air flow into the fuel bed from underneath, as and when required. In effect it is a means of turning up the gas; increasing the gas 100 flow from the fuel bed (the gas producer) at will, as required.

It will also be noted that my device is adapted normally to permit the uninterrupted course of draft in the accustomed manner 105 in a wide range of heating units; that is, the regular and accustomed ash pit draft management is not disorganized, but when desired, all the elements of the ash pit draft may function normally.

What I claim is:—

1. In combination with a heating furnace, having a hinged ashpit door with a draft opening having margins in a plane inclined to the perpendicular, a fan and motor and a 115 housing therefor, an adapter comprising a chambered formation open to the draft opening and to the fan and motor housing, said adapter having cooperating margins in a plane corresponding to that of the margins 120 of the draft opening, secured to and supported by the ashpit door and secured to and supporting the said housing, and horizontally slidable shutters positioned between the adapter and the fan and motor housing. 125

2. In combination with a heating furnace, having a hinged ashpit door with a draft opening having margins in a plane inclined to the perpendicular, a fan and motor and a housing therefor, an adapter comprising a 130

chambered formation open to the draft opening and to the fan and motor housing, said adapter having cooperating margins in a plane corresponding to that of the margins 5 of the draft opening, secured to and supported by the ashpit door and secured to and supporting the said housing, the adjacent walls of the adapter and of the fan and motor housing cooperating to form horizontal ways for 10 shutters and shutters slidable therein.
